PACKAGE ASSORTING MACHINE

John R. Sousa, Silver Spring, Md.

Application November 16, 1948, Serial No. 60,269

9 Claims. (Cl. 214—11)

1

This invention relates to parcel carriers or conveyors of the type including sorting elements and adapted to handle packages of various sizes, mail, and similar articles or devices, and in particular a carrier traveling in a horizontally disposed track with a plurality of stations positioned in the track and with means positioned in the different stations for tripping operating devices for arresting the carrier, and also means for actuating the carrier to and from the stations.

The purpose of this invention is to provide improvements in sorting and distributing parcel or package carriers wherein it is only necessary for an operator to press one button as he places a parcel in a carrier and the carrier delivers the parcel to a selected station and immediately returns for another parcel.

This invention is an improvement over the parcel sorting devices of my prior Patents #1,521,-405; #1,718,087; #1,740,378; and #1,838,460.

In these parcel sorting devices of the prior patents and also in similar devices in the art, it has been difficult to set the trips and actuate a carrier to and from a station with a single button or lever, particularly as the reversing clutches require separate operating means. With this thought in mind, this invention contemplates a carrier rotatably mounted in a horizontally disposed track with the carrier operated by cables and with the cables controlled by reversing clutches operated by trip instrumentalities at the different stations in the track.

The object of this invention is, therefore, to provide an improved parcel sorting and distributing carrier or conveyor wherein reversing clutches for returning the carrier are automatically operated as the carrier reaches a station in which the trip elements have been set.

Another object of the invention is to provide carrier actuating instrumentalities in a parcel sorting conveyor in which two clutches are actuated by a single motor with one clutch operating means for taking a carrier to a station and the other clutch operating means for returning the carrier.

Another object of the invention is to provide an improved trip mechanism for parcel conveying and sorting devices wherein a single button or lever sets means for removing parcels from the carrier and also means for starting the return movement of the carrier.

Another object of the invention is to provide improved means for mounting friction cone clutches in parcel sorting devices wherein forward and reverse clutches are mounted on a

2

common shaft and operated by clutch levers connected to a common bar.

A further object of the invention is to provide an improved parcel sorting device having automatic return clutches for a carrier therein, which is of a comparatively simple and economical construction.

With these and other objects and advantages in view, the invention consists of the new and useful combination, construction, and arrangement of parts as hereinafter more fully described, set forth in the claims appended hereto, and disclosed in the accompanying drawings forming part hereof, wherein:

15 Figure 1 is a side elevational view of the improved parcel sorting conveyor with parts broken away;

Figure 2 is a similar view showing the upper part of the conveyor with only one set of trip 20 actuating instrumentalities thereon, with parts broken away, and with other parts omitted for the purpose of illustration;

Figure 3 is a plan view of the parcel sorting conveyor showing the trip of the last station 25 thereof in the position of arresting the carrier;

Figure 4 is a detail showing the arrangement of the trip levers with the levers set in the tripping position;

Figure 5 is a part longitudinal section through 30 the conveyor with the ends broken away and showing the carrier in the position of engaging the trip levers with the levers set as shown in Figure 4;

Figure 6 is a similar fragmentary section at the 35 starting end of the conveyor illustrating the position of the lever for returning the trip actuating levers as the carrier returns to the starting position;

Figure 7 is a fragmentary perspective view illustrating the trip and operating levers with the trip of the last station set in the position for arresting the carrier;

Figure 8 is an end elevational view illustrating the relative positions of the cone clutches and 40 pulleys with the motor for operating the clutches and showing the clutches in the neutral position;

Figure 9 is a similar view through the upper part of the frame with the lower part broken away and with the clutches set in the position of actuating the carrier forwardly to deliver a parcel to a station;

Figure 10 is a similar view, also with parts broken away, and showing the clutches in the reverse position;

Figure 11 is a longitudinal section through the

clutch shaft with the clutches shown in section and with the shaft in elevation and showing the clutches in a neutral position and with parts of the mounting elements broken away;

Figure 12 is a similar view showing the clutches in the position of actuating the carrier forwardly;

Figure 13 is a detail showing a side view of one of the hangers for supporting the intermediate part of the clutch shaft;

Figure 14 is a cross section through the conveyor showing the parcel carrier in one of the stations thereof;

Figure 15 is a detail showing a longitudinal section through the conveyor with the ends broken away and with the carrier therein shown in elevation;

Figure 16 is a detail showing a cushioning cylinder for arresting the carrier at the end of its travel;

Figure 17 is a detail showing a small cam on the side of the trailing end of the carrier;

Figure 18 is a detail illustrating the path of the cam shown in Figure 17 as it passes over a trip lever of one of the stations;

Figure 19 is a similar view showing the trip lever set to engage the cam;

Figure 20 is a similar view showing the trip lever in the position to which it has been moved by the cam in which position the parts are released and the return movement of the carrier is initiated.

Referring now to the drawings wherein like reference characters denote corresponding parts, the sorting parcel carrier of this invention includes a carrier 10 having rollers 11 positioned to ride on tracks 12 and 13 with bars 14 positioned below the tracks for supporting operating parts of the machine.

The rails 12 and 13 on which the carrier 10 is mounted by the rollers 11 are supported in a frame having vertical posts 15 connected, at the upper ends, by horizontally disposed bars 16, and the extended ends of the rails are supported by posts 17 on which a platform 18 is provided for supporting a motor 19.

At the opposite end of the frame, and supported on the end post 15 is an upper frame having vertically disposed struts 20 and 21 which are positioned on horizontal beams 22 and a transversely disposed horizontally positioned beam 23 is mounted on the strut 20 which provides a support for the operating handles 24 which are pivotally mounted thereon by pins 25. The outer face of the bar 23 provides an area 26 for a name plate to correspond with the levers 24.

The levers 24 are provided with arms 27 which are connected by rods 28 to one arm of levers 29 and the levers are pivotally mounted by pins 30 on a transverse beam 31, as shown in Figure 3. The levers 29 are rigidly mounted on the pins 30 and the pins are also provided with arms 32 which are connected by rods 33 to bell cranks 34 that are pivotally mounted on a pin 35. The opposite arms of the bell cranks 34 are connected by rods 36 to the ends of arms 37 which extend downwardly from transverse shafts 38 on which fingers 39 are provided. The levers 24 at one side are connected directly to the arms 37 by rods 36a, as shown in Figure 3. The fingers 39 are normally horizontally positioned and when one of the hand levers 24 is moved downwardly from the position shown in Figure 1 to that shown in Figure 2, the rods, levers, and bell cranks actuate the shaft 38 to the position shown by the last shaft shown in Figure 7 with the fingers 39

extended vertically upward. In this movement, the arms 37 move from the position shown by the two shafts 38 to the position shown by the single shaft wherein the fingers 39 extend upward. In this position, a pin 40 on the inner surface of the arms 37 engages a lever 41 which is pivotally mounted on a bar 42 by a pin 43. The lever 42 is also pivotally connected to a clutch bar 44 by a pin 45. The bar 42 may be provided with depending hooks 46 that may be used for holding parcels or the like, when desired.

The opposite ends of the shafts 38 are provided with arms 47 from the lower ends of which pins 48 extend and the pins 48 are positioned to engage projections 49 on trip levers 50 which are pivotally mounted by pins 51 on lower rails 14. The trip levers 50 are also provided with laterally extending fingers 52 that are positioned to be engaged by a cam 53 on the lower rear corner of the carrier 10 when the shaft 38 associated therewith has been turned with the fingers 39 thereof extended upward. It will be noted in Figure 18 that when the fingers 39 are horizontally disposed so that the trip levers 50 hang downwardly with the lower end resting on the shafts 38, the cam 53 passes over the fingers 52.

The clutch operating levers 41 extend vertically upward when the machine is inoperative and when a parcel has been placed in the carrier and one of the hand levers 24 is actuated, the pins 40 of the arms 37 engage the associated lever 41 moving all of the levers 41 with the bar 42 forwardly, thereby actuating the clutch to start the operation of the carrier. With the same movement the arm 47 on the opposite end of the shaft 38 moves upwardly to position the trip lever 50 so that the finger 52 thereof is in the path of the cam 53, whereby the cam will raise the trip lever 50, releasing the pin 48 so that the pin and arm 47 will drop downward actuating the arm 37 to release the lever 41.

A rod 55 is connected to the end of the clutch operating bar 44 and the opposite end of the rod 55 is connected to a bell crank 56 which is pivotally mounted by a pin 57 in the brackets 58 and the opposite end of the bell crank is connected to a bar 59 which is connected to a spring 60 in a bracket 61. The bar 59 is pivotally connected to the ends of the clutch levers 62 and 63 suspended from hangers 64 and 65 and the levers are provided with slots 66 and 67, respectively. The slots 66 and 67 are positioned to receive pins 68 and 69 on rings 70 and 71 of the sliding clutches 72 and 73, respectively. The clutch 72 is provided with a cone shaped friction face 74 that is positioned to engage a conical inner surface 75 of a clutch pulley 76 which is freely mounted on a clutch shaft 77. The clutch 72 is slidable on and keyed to the shaft by a clutch key 78 and resiliently held in free position by a spring 79. An inner clutch collar 80 is positioned on the shaft in the clutch pulley and a thrust bearing 81 is positioned on the shaft 77 between the clutch pulley and hanger 82. A similar hanger 83 with a thrust bearing 84 is positioned at the end of the clutch pulley 85 in which the clutch 73 is positioned. The lower ends of the hangers are provided with slots, as indicated by the numeral 86 that receive the clutch shaft 77 and the hangers are carried by a cross-bar 87, as shown in Figures 8, 9 and 10.

The clutch pulley 76 is driven from a cone pulley 88 on a jackshaft 89 by a belt 90 and the clutch pulley 85 is driven by a belt from a cone pulley 91 on a jackshaft 92, as shown in Figure 8.

The jackshaft 92 is driven from the motor 19 by pulleys A and B with a belt C and the jackshaft 89 is driven from the jackshaft 92 by gears D and E which reverse the direction of rotation of the shaft 89 in relation to that of the shaft 92.

The clutch shaft 77 is provided with cable pulleys 93 and 94 over which cables 95 and 96 are trained and similar pulleys 97 and 98 are provided at the starting end of the conveyor, and with the ends of the cables connected to the sides of the carrier 10, as shown at the points 99 and 100, Figure 15, the carrier will travel backward and forward, as the cables are actuated. The sides of the carrier 10 are provided with horizontally disposed rollers 101 that engage side flanges of the rails of the track to provide lateral guiding means to facilitate the travel of the carrier.

The starting end of the conveyor is provided with a crank 102 pivotally mounted in a bearing 103 formed in the upper rail of the side of the frame and this crank extends downwardly into the path of an angle 104 on the carrier wherein it will be engaged by the angle as the carrier returns to the starting position. The crank is provided with a downwardly extending arm 105 that is connected to the clutch bar 44 by a rod 106, as shown in Figures 6 and 14, and as the carrier returns to the starting position, the crank 102 will be moved upwardly and the bar 44 will be drawn forwardly, positioning the levers 41 vertically and returning the clutch operating levers to the neutral position.

The carrier 10 is also provided with a stop 107 that is positioned to engage a head 108 on a piston rod 109 of a piston 110 in an air cylinder 111, as shown in Figure 16. The cylinder is provided with a spring 112 and a bleeder opening 113 is provided in the end thereof with a thumb screw 114 having a point in the opening providing a needle valve to regulate the flow of fluid through the opening. It will be noted that as the stop 107 engages the head 108 the travel of the carrier 10 will be arrested and the cylinder will provide cushioning means to reduce the striking force thereof.

The main supporting frame of the conveyor, formed by the members 15 and 16 is divided into stations with one of the shafts 38 in each station and receiving bags or bins 115 may be provided below the track in the station, wherein with the bag suspended by the hooks 46, parcels will be dropped therein as the carrier reaches one of the stations.

It will be understood that these sorting or distributing conveyors may be used in batteries, positioned side by side or one above the other and each unit may be of any suitable length, having any number of stations desired.

In use, the carrier 10 is positioned at the starting end, as shown in Figure 1 and when one of the levers 24 is actuated, the shaft 38 corresponding therewith, is turned with the fingers 39 thereon extended upwardly, as shown in Figure 7, and with the trip lever 50 at the opposite end of the shaft elevated by the pin 48 on the arm 47. The pin 48 provides locking means retaining the shaft in the position with the fingers 39 extended upwardly and with the levers 41 sloping forwardly until the trip lever 50 is released. Drawing the arm 47 forwardly also moves the levers 41 thereby drawing the clutch bar 44 and pulling the clutch levers from the position shown in Figure 8 to that shown in Figure 9 wherein the clutch pulley 85 will rotate the clutch shaft and

draw the carrier 10 along the track by the cables. The lower surface of the carrier 10 is provided with slots 116 which receive the fingers 39 and as the carrier arrives at the station corresponding with the lever 24, that has been actuated, the cam 53 will engage the finger 52, thereby elevating the trip lever 50 and releasing the pin 48, at which time the shaft 38 is released and the spring 60 draws the clutch bar 44 toward the clutch end of the frame and at the same time moves the clutch levers from the position shown in Figure 9 to that shown in Figure 10 wherein the clutch pulley 85 is released and the clutch pulley 76 is driven by the jackshaft 89, which reverses the direction of travel of the cable, thereby returning the carrier to the starting position. As the carrier arrives at the starting position, it will engage the crank 102 and, as hereinbefore described, return the elements to the neutral position in which the parts are inoperative.

It will be understood that modifications may be made in the design and arrangement of parts without departing from the spirit of the invention.

What is claimed is:

1. A parcel sorting conveyor comprising a horizontally disposed track, a carrier mounted to travel in said track, said track including a plurality of stations, cables trained over pulleys at opposite ends of the track and connected to the carrier, means operating the cables, means in the operating means for reversing the direction of the travel of the cables and carrier, trip means at the stations for stopping the cable operating means to stop the carrier, a plurality of manually actuated levers positioned on a shaft extended across the starting end of the track, bell cranks pivotally mounted on a vertically disposed shaft at one side of the track, means independently connecting the levers to the bell cranks, rods connecting the bell cranks independently to levers at the different stations for setting the trip means from the starting end of the conveyor, means actuated by the trip means for starting the said reversing means as the carrier arrives at the station, and means actuated by the carrier as it returns to the starting position for actuating the cable operating means to the inoperative position.

2. A parcel sorting conveyor comprising a horizontally disposed track, having upper and lower rails, a carrier mounted to travel in said track, said track including a plurality of stations, cables at opposite sides of the track trained over pulleys at opposite ends thereof and connected to the carrier, means operating the cables, means in the operating means for reversing the direction of the travel of the cables and carrier, trip means at each station for removing parcels from the carrier, a plurality of manually actuated levers positioned on a shaft extended across the starting end of the track, bell cranks pivotally mounted on a vertically disposed shaft at one side of the track, means independently connecting the levers to the bell cranks, rods connecting the bell cranks independently to levers at the different stations for setting the trip means and starting the cable operating means from the starting end of the conveyor, means retaining the trip means in the position for removing parcels from the carrier until the carrier arrives at the station, means releasing the trip means and actuating the reversing means as a carrier arrives at the station, and means actuated by the carrier as it returns to the starting position for actuating

the cable operating means to the inoperative position.

3. A parcel sorting conveyor comprising a horizontally disposed track having upper and lower rails, a carrier having rollers on the sides thereof mounted to travel in said track, said track including a plurality of stations, cables trained over pulleys at opposite ends of the track and connected to the carrier, a clutch shaft on which the pulleys at one end of the track are mounted, cone clutch pulleys mounted on the clutch shaft, means driving the said cone clutch pulleys in opposite directions, trip means for removing parcels from the carrier as the carrier arrives at a station, a plurality of manually actuated levers positioned on a shaft extended across the starting end of the track, bell cranks pivotally mounted on a vertically disposed shaft at one side of the track, means independently connecting the levers to the bell cranks, rods connecting the bell cranks independently to levers at the different stations for setting the trip means from the starting end of the conveyor, said setting means including means for starting one of the cone clutch pulleys to actuate the carrier from the starting point to the station, and means releasing the former cone clutch pulley and actuating another cone clutch pulley to reverse the direction of travel of the carrier as the carrier arrives at the station in which the trip means is set to remove a parcel from the carrier.

4. A parcel sorting conveyor comprising a horizontally disposed track having upper and lower rails, a carrier having rollers on the sides mounted to travel in said track, said track including a plurality of stations, cables trained over pulleys at opposite ends of the track and connected to the carrier, a clutch shaft on which the cable pulleys at one end of the conveyor are mounted, a pair of clutch pulleys mounted on the clutch shaft, a pair of jackshafts positioned parallel to the clutch shaft and spaced therefrom, means actuating the clutch shaft from the jackshaft through the cone clutch pulleys, means rotating the jackshaft in opposite position, trip means at the station for removing parcels from the carrier, a plurality of manually actuated levers positioned on a shaft extended across the starting end of the track, bell cranks pivotally mounted on a vertically disposed shaft at one side of the track, means independently connecting the levers to the bell cranks, rods connecting the bell cranks independently to levers at the different stations for setting the trip means from the starting end of the conveyor, means actuating the clutch of one of the cone clutch pulleys by the trip setting means to start the carrier away from the starting end of the conveyor, and means actuating the clutch of the other cone clutch pulley to return the carrier to the starting position as the carrier arrives at a station.

5. A parcel sorting conveyor comprising a horizontally disposed track, a carrier with rollers thereon mounted to travel in said track, said track including a plurality of stations, cables trained over pulleys at opposite ends of the track and connected to the carrier, a clutch shaft on which the cable pulleys at one end of the track are positioned, a pair of cone clutch pulleys mounted on said clutch shaft, a pair of jackshafts having cone pulleys thereon aligned with the cone pulleys of the clutch shaft, belts on the said cone and clutch pulleys, gears driving one jackshaft in a direction opposite to that of the other, means driving the said jackshafts, clutch levers for actuating the clutch elements of the cone clutch pulleys, a spring for actuating the clutch levers to the position of reversing the direction of travel of the carrier, trip means for removing parcels from the carrier, said trip means positioned at the stations, means setting the trip means and actuating the clutch levers for starting the carrier from the starting position to the station, means retaining the trip means of the stations in a set position until the carrier arrives at the station, means releasing the retaining means and springs as the carrier arrives at the station in which the trip means is set, cushioning means for stopping the carrier as it returns to the starting position, and stop means positioned to be engaged by the carrier

clutch levers for actuating the clutch elements of the cone clutch pulleys, a spring for actuating the clutch levers to the position of reversing the direction of travel of the carrier, trip means for removing parcels from the carrier, said trip means positioned at the stations, means setting the trip means and actuating the clutch levers for starting the carrier from the starting position to the station, means retaining the trip means of the stations in the set position until the carrier arrives at the station, and means releasing the retaining means and springs as the carrier arrives at the station in which the trip means is set.

15 6. A parcel sorting conveyor comprising a horizontally disposed track, a carrier with rollers thereon mounted to travel in said track, said track including a plurality of stations, cables trained over pulleys at opposite ends of the track and connected to the carrier, a clutch shaft on which the cable pulleys at one end of the track are positioned, a pair of cone clutch pulleys mounted on said clutch shafts, a pair of jackshafts having cone pulleys thereon aligned with the cone pulleys of the clutch shaft, belts on the said cone and clutch pulleys, gears driving one jackshaft in a direction opposite to that of the other, means driving the said jackshafts, clutch levers for actuating the clutch elements of the cone clutch pulleys, a spring for actuating the clutch levers to the position of reversing the direction of travel of the carrier, trip means for removing the parcels from the carrier, said trip means positioned at the stations, means setting the trip means and actuating the clutch levers for starting the carrier from the starting position to the station, means retaining the trip means of the stations in the set position until the carrier arrives at the station, means releasing the retaining means and springs as the carrier arrives at the station in which the trip means is set, and cushioning means for stopping the carrier as it returns to the starting position.

45 7. A parcel sorting conveyor comprising a horizontally disposed track, a carrier with rollers thereon mounted to travel in said track, said track including a plurality of stations, cables trained over pulleys at opposite ends of the track and connected to the carrier, a clutch shaft on which the cable pulleys at one end of the track are positioned, a pair of cone clutch pulleys mounted on said clutch shafts, a pair of jackshafts having cone pulleys thereon aligned with the cone pulleys of the clutch shaft, belts on the said cone and clutch pulleys, gears driving one jackshaft, in a direction opposite to that of the other, means driving the said jackshafts, clutch levers for actuating the clutch elements of the cone clutch pulleys, a spring for actuating the clutch levers to the position of reversing the direction of travel of the carrier, trip means for removing parcels from the carrier, said trip means positioned at the stations, means setting the trip means and actuating the clutch levers for starting the carrier from the starting position to the station, means retaining the trip means of the stations in a set position until the carrier arrives at the station, means releasing the retaining means and springs as the carrier arrives at the station in which the trip means is set, cushioning means for stopping the carrier as it returns to the starting position, and stop means positioned to be engaged by the carrier

75 as it returns to the starting position for actuat-

ing the clutch levers whereby the clutch elements assume neutral positions.

8. A parcel sorting conveyor comprising a horizontally disposed track, a carrier with rollers thereon mounted to travel in said track, said track including a plurality of stations, cables trained over pulleys at opposite ends of the track and connected to the carrier, a clutch shaft on which the cable pulleys at one end of the track are positioned, a pair of cone clutch pulleys mounted on said clutch shaft, a pair of jackshafts having cone pulleys thereon aligned with the cone pulleys of the clutch shaft, belts on the said cone and clutch pulleys, gears driving one jackshaft in a direction opposite to that of the other, means driving the said jackshafts, clutch levers for actuating the clutch elements of the cone clutch pulleys, a spring for actuating the clutch levers to the position of reversing the direction of travel of the carrier, trip means for removing parcels from the carrier, said trip means positioned at the stations, a plurality of setting levers at the starting end of the conveyor corresponding with the stations, means connecting the setting levers to the parcel removing means at the stations, means connecting the setting levers to the clutch levers for actuating the clutch levers to start the carrier from the starting position, means retaining the parcel removing means of the station in the set position until the carrier arrives at the station, and means releasing the retaining means as the carrier arrives at the station in which the parcel removing means is set.

9. A parcel sorting conveyor comprising a horizontally disposed track, a carrier with rollers thereon mounted to travel in said track, said track

including a plurality of stations, cables trained over pulleys at opposite ends of the track and connected to the carrier, a clutch shaft on which the cable pulleys at one end of the track are positioned, a pair of cone clutch pulleys mounted on said clutch shaft, a pair of jackshafts having cone pulleys thereon aligned with the cone pulleys of the clutch shaft, belts on the said cone and clutch pulleys, gears driving one jackshaft in a direction opposite to that of the other, means driving the said jackshafts, clutch levers for actuating the clutch elements of the cone clutch pulleys, a spring for actuating the clutch levers to the position of reversing the direction of travel of the carrier, transverse shafts in the stations having fingers thereon for removing parcels from the carrier, means actuating the shaft to set the fingers in the position of removing parcels from the carrier and also for actuating the clutch levers for starting the carrier from the starting position, means retaining the shaft with the fingers thereon in the parcel removing position, and means releasing the shaft whereby the clutch levers are actuated to reverse the direction of travel of the carrier as the carrier arrives at the station in which the fingers are set in the parcel removing position.
